MULTIPLE STRING HOLDING DEVICE

Filed Oct. 15, 1927

INVENTOR:
KASIMIR MILOSEWICZ.
per McHeide.
ATTORNEY.

UNITED STATES PATENT OFFICE

KASIMIR MILOSEWICZ, OF LONDON, ENGLAND

MULTIPLE STRING-HOLDING DEVICE

Application filed October 15, 1927. Serial No. 226,468.

This invention relates to an improved construction of multiple string holding devices, it being understood that by the term string as used in this specification and the claims hereof I include not only slender lines thinner than a cord and thicker than a thread, but also twine, cord, thread, wire, and slender lines in general.

One of the objects of this invention is to provide a multiple string holding device which is capable of permitting the strings to be withdrawn in any desired direction, particularly from different points of the compass, whereby to permit, for example, a group of packers to stand in a group round the device with each packer commanding a supply of string without having to impede any of the others.

Another object is to provide such a device as a compact strong, sturdy, lasting, and dependable structure.

The invention accordingly consists in the features of construction, combinations of elements, and arrangement of parts as will be exemplified in the structure to be hereinafter set forth and the scope of the application of which will be indicated in the following claims.

In the accompanying drawings, in which is shewn by way of example a constructional embodiment of the invention as suited to hold a plurality of balls of strings,

Fig. 1 is a side view of the device.

Fig. 2 a plan view of the device when closed.

Fig. 3 a plan view of the device when open.

Fig. 4 is an end view of the device when open.

Similar reference characters refer to similar parts throughout the several views of the drawings.

In the drawings, 1 is a long narrow box adapted to carry therein in spaced relation a plurality of compact sources of supply of string, which sources may be in the form of balls of string 2, the holes in which may be engaged by posts 3 upstanding from the bottom of the box 1, for example, upstanding substantially centrally of the separate compartments into which the box 1 may be divided by the partitions 4.

The compact sources of supply of string may be otherwise provided, for example, the string may be wound on spools or rollers adapted to be mounted rotatably in spaced relation in the box 1.

With the string holding box is associated multiple directing means for positively directing the withdrawing ends 5 of the strings 2 in any desired direction, for example, to different points of the compass.

As shewn the box 1 is provided with a cover 6 which is preferably hinged at 7 to the box 1 and is preferably furnished with some suitable fastening 8. The backward movement of the hinged cover may be suitably limited by the provision of knuckle jointed levers 15.

In the cover 6 are openings 9 corresponding to the number of balls of string, through which to permit the withdrawing ends of the strings to pass.

On the cover 7 and movable therewith is a staple-like frame comprising side-pieces 11, 12, bridged by a cross-piece 13.

Depending downwardly from the cross-piece 13 are guides, for example, eyes 14, and projecting outwardly from the opposite edges of the side-pieces 11 and 12 are similar guides, for example, further eyes 14.

These guides on the cross-piece 13 and also on the side-pieces 11 and 12 permit the withdrawing ends of the string to be directed to the same side or to opposite sides of the device, or, as shewn, to different or various points of the compass away from the device.

I am aware that prior to my invention there has been proposed a twine holder for stringing hop-yards, consisting of a compartmented box having a hinged cover, said hinged cover having eyes for the passage of the twines and guides on the top side through which the twines pass. The said holder has one or more straps or bands for attaching the same to the person. Such a combination is not included in the present claims.

What I claim is:—

1. As a new article of manufacture a multiple string holding device, comprising in combination, a holder for a plurality of balls of string, a hinged cover for said holder, said

cover having holes therein for the passage of the withdrawing ends of said strings, a frame consisting of side-pieces bridged by a cross-piece rising from said cover and movable therewith, and a multiple of directing means on the under side of said cross-piece for positively directing the withdrawing ends of said strings in predetermined directions.

5. 2. As a new article of manufacture a multiple string holding device, comprising in combination, a holder for a plurality of balls of string, a hinged cover for said holder, said cover having holes therein for the passage of the withdrawing ends of said strings, a frame 10 consisting of side-pieces bridged by a cross-piece rising from said cover and movable therewith, and a multiple of directing means 15 on the under side of said cross-piece and on the side-pieces for positively directing the 20 withdrawing ends of said strings in predetermined directions.

In testimony whereof, I affix my signature.
KASIMIR MILOSEWICZ.
